UNITED STATES PATENT OFFICE.

CHARLES JOSEPH VLASAK, OF ST. LOUIS, MISSOURI.

FUEL-IGNITER.

1,381,951.

Specification of Letters Patent. Patented June 21, 1921.

Application filed January 18, 1921. Serial No. 438,225.

To all whom it may concern:

Be it known that I, CHARLES JOSEPH VLASAK, a citizen of the United States, and a resident of St. Louis, in the State of Missouri, have invented certain new and useful Improvements in Fuel-Igniters, of which the following is a specification.

My present invention relates generally to fuel igniters and more particularly to devices for igniting fuel in stoves, furnaces, grates and the like without the necessity of kindlings and paper, my primary object being the provision of a simple, inexpensive and readily adjustable device of this nature adaptable to convenient support and capable of easy manipulation and adjustment.

In the accompanying drawing which illustrates my present invention and forms a part of this specification,

20 Figure 1 is a detail perspective view illustrating the practical application of my invention,

Fig. 2 is a detail perspective view of the supporting cross piece,

25 Fig. 3 is a similar view of the shiftable supporting bar,

Fig. 4 is another detail perspective view of the pivot supporting clamp, and

30 Fig. 5 is a cross section taken through my improvements in line with the pivot forming clamp.

Referring now to these figures my invention proposes an apparatus including a burner pipe 10, one end of which is provided 35 with lengthwise series of burner openings 11 in a curved part 12 beyond a gooseneck bend 13 which adapts this, the burner end, of the pipe to convenient operation in connection with either a low down grate 14 40 such as shown in connection with a stove partly seen at 15 in full lines in Fig. 1 and the grate 16 of a furnace partly seen at 17 in dotted lines in the same figure.

The burner end of the burner pipe 10 may 45 be plugged or otherwise closed and its opposite curved end 18 is preferably provided with a handle 19 and has means, for instance the usual tapering nipple, for the convenient connection of a flexible gas supply pipe or hose 20.

The support of the burner includes a flat cross piece 21 whose opposite ends are preferably curved and bifurcated to provide downturned spurs 22 adapted to straddle or 55 otherwise engage portions of a stove, grate or furnace, it being obvious that the burner

pipe needs but a steadyng purchase rather than an actual support in view of the fact that the handle 19 of the burner pipe is grasped at all times in use.

Midway between its ends the cross piece 21 has an opening 23 receiving a pivot pin 24 also extending through an aperture 25 at one end of an adjusting bar 26, the latter being thus adapted to swing in a horizontal plane with respect to the cross piece.

Adjacent to its free end the adjusting bar 26 has an opening 27 and through this opening a pin 28 extends, this pin projecting through a central opening 29 of a U-shaped pivot clamp 30, having upstanding side ears 31 at opposite sides of the bar 26. These ears have openings 32 adjacent to their upper ends to receive a clamping bolt 33 and also have openings 34 below the openings 32, to receive the ends of a diametrical pin 35 projecting through the burner pipe 10 adjacent to its curved handle receiving end, which the ears 31 are adapted to clamp.

Thus with the parts assembled as shown 80 in Figs. 1 and 5, the handle 19 may be depressed to shift the opposite or burner end of the pipe vertically and upwardly to the dotted line position of Fig. 1 and in this way adapted to the relatively high grates of 85 some furnaces as compared to the low down grates of stoves, while by shifting the handle from side to side the burner pipe will be horizontally adjusted on the pivot 24 connecting the adjusting bar 26 with the 90 cross piece 21 so that the burner may in this way be swung laterally beneath the grate.

My invention proposes a simple, inexpensive apparatus which may be quickly inserted in and removed from operative position, which may be readily manipulated and adjusted in operation, which is simple in construction and will be effective and durable 95 in use.

I claim:

1. A fuel igniter including a burner pipe having one free curved end provided with burner forming means and having a handle at its opposite end, a supporting cross piece having support engaging means at its opposite ends, and an adjusting bar pivoted at one end to the cross piece intermediate the ends of the latter and having a pivotal mounting adjacent to its opposite end for 105 the burner pipe and on which the latter is vertically swingable.

2. A fuel igniter including a burner pipe having one free end provided with burner forming means and having a handle adjacent to its opposite end, a pivotal mounting 5 for the burner pipe adjacent to its handle and upon which the burner pipe is vertically swingable, and a frame including a cross

piece having means at its opposite ends to engage a support and an adjusting bar supporting the pivotal mounting of the burner 10 pipe adjacent to one end and having its opposite end pivoted to the cross piece.

CHARLES JOSEPH VLASAK,
